AUTOMATIC VOLUME CONTROL CIRCUIT

Waldemar J. Poch, Moorestown, N. J., assignor to
 Radio Corporation of America, a corporation of
 Delaware

Application May 13, 1943, Serial No. 486,789

8 Claims. (Cl. 178—7.2)

1

The present invention is related to television circuits and particularly to television amplifier circuits, and is mainly concerned with automatically setting or controlling the video output signal level in such amplifier circuits.

The circuit to be described is intended primarily for use with television apparatus and systems wherein the video or picture signals representing the scene being scanned result from the scanning of a storage element, such as the mosaic element of cathode ray scanning or camera tubes of the general types known in the art as the "Iconoscope," the "Image Iconoscope" and the "Orthicon" for instance, all of which have been generally described by pages 94 et seq. of the book "Principles of Television Engineering," by D. G. Fink, and published in 1940 by McGraw-Hill Book Co., Inc., of New York.

In such systems, an optical image of the scene to be televised is cast upon the mosaic electrode of the scanning tube and produces thereon electrostatic charges of magnitudes proportional to the image brightness. When the charges so produced are scanned by a cathode ray scanning beam, output signals, known as the video or picture signals, result and are released to a signal utilization circuit, which usually includes one or more amplifier tubes, among other elements.

The level of such video signals is subject to change due to both the scanning tube itself and changes in the voltage applied to operate the scanning tube and other tubes of the system. This invention relates to a system by which the output signal level can be maintained at substantially constant level through appropriately controlled operating circuits, known generally as automatic volume control elements.

In the prior art, some circuits have heretofore been provided for establishing an automatic volume control signal to compensate for changes in output signal level from the scanning tube. However, the circuits of the prior art do not satisfactorily provide an adequate control due to the fact that video, shading, dark-spot correction and many other forms of signals are frequently developed during the blanking periods of the scanning cycle in the television system, it being, of course, understood that this invention is intended for use with a storage type of scanning or camera tube, as above suggested and indicated. Such prior art systems tended to establish any control of the signal level in such a way that the resulting control voltage or energy was not always a signal which was measured by the video signal itself.

2

but rather by a mixture of it with a plurality of undesired or compensating signals.

It is, therefore, an object of the present invention to provide an automatic volume control circuit for television apparatus which will operate to control output signal level only during periods of useful video signal transmission, but which, during periods of video signal interruption when the blanking or synchronizing signals are to be transmitted, the automatic volume control will not be effective and no automatic volume control signal energy will be developed. In this way, the present invention has as one of its main objectives, that of providing an automatic volume control system for a television amplifier circuit where the control operates substantially only during the period of useful video signal transmission and is effective upon the video signal transmission rather than upon other signals.

Another object of the invention is that of providing an automatic volume control system for television which operates substantially only during the periods between successive blanking signal energy pulses, where the blanking signals are caused, as known in the art, to follow each line of video signal transmission.

Still other objects of the invention are those of providing a sensitive automatic volume control which is controlled positively in its cycle or period of operation and which, when so controlled, will respond to producing an efficient and accurate control signal by means of a relatively simple circuit arrangement in which the use of excess parts and weight is avoided.

Other objects of the invention are those of overcoming one or more known defects of the prior art systems of control by means of an efficient and inexpensive circuit addition which is both positive and sensitive in its operation.

Still other objects and advantages of the invention will become apparent from the specification to follow when the specification is read in connection with the accompanying drawing, of which the single figure thereof illustrates one suitable form of circuit arrangement by which the invention may be practiced.

Referring now to the drawing, it will be seen that the invention essentially comprises the use of a diode tube which derives energy from the output of a suitable video amplifier or clipper tube unit, with provisions having been made to introduce the blanking signal energy upon the diode element in such a manner as to key it to an inoperative state during the periods of and for the duration of the blanking signal energy pulses.

In the circuit illustrated, the video signals produced initially are the output signals which result from scanning the mosaic element 11 contained within a television camera tube 15. The camera tube 15, may, for the purpose of describing one form of device, be considered as one of the type known in the art as the "Iconoscope" which has been described widely in the literature by Zworykin, Iams, Rose and others, as, for instance, the book above mentioned, and thus requires little or no further reference herein as to its specific properties or construction.

For developing the television video or picture signals, the optical image of the scene 17 to be transmitted is focused upon the mosaic element 11 of the camera tube 15 by means of a suitable optical system 19, conventionally illustrated. When this is done, electrostatic charges of magnitudes proportional to the intensity of light and shadow of the optical image are built up across the mosaic element. In order to release these charges to produce the output video signals, a scanning cathode ray beam 21 is arranged to scan the mosaic in a suitable pattern under the influence of a suitable deflecting field. The scanning is carried forward in two mutually perpendicular directions by means of suitable deflecting elements 23 and 24, which are herein illustrated as electromagnetic coils, but which could be electrostatic deflecting plates, or they could be electromagnetic coils for one direction of deflection, and electrostatic deflecting plates for the other direction of deflection.

The video signals which are thus produced by the scanning beam action serving to neutralize the stored charges on the mosaic in sequence are then amplified, first in an amplifier 25 which has generally become known as the pre-amplifier since it is located closely adjacent the scanning tube and precedes the general main amplifier unit 27 to which its output signals are supplied. The amplifier 25 is of a purely conventional type and it, like the other amplifiers to be mentioned and diagrammatically illustrated, has been so widely described in the published literature as to require neither detailed explanation of its circuit arrangement nor its specific manner of functioning.

As was above stated, the signal output from the preamplifier 25 is supplied to another amplifier unit 27 which usually comprises several stages of amplification and is frequently termed the "line amplifier" or "voltage amplifier." It will be in one of the stages of this line amplifier unit 27 that the control signal energy to be developed by the circuit elements herein to be described is introduced to control the resulting output signal energy level.

Output energy from the line amplifier 27 is then supplied to a combining amplifier unit 29. In this last named amplifier unit (which also includes one or more tubes under most conditions), it is customary to introduce an appropriate signal to care for and compensate, as far as possible, for a distortion in the video signal which is known in the art as the "dark spot." A signal of this compensating character is introduced to compensate for the above named effect because of the presence of such distortion due to an inherent property of the assumed type of scanning tube. The correcting signal thus becomes known as the "shading control signal" or the "dark spot correction signal" and may be of the form already explained in the literature.

Where the amplifier units are so set up that the D. C. correction will not again be "lost" (due, for example, to the so-called A. C. coupling circuits), the D. C. component may be added in the combining amplifier unit 29 as a so-called "D. C. correction" signal. Similarly, the blanking and synchronizing (also called the "sync") signals may be added in the combining amplifier unit. These signals are, respectively, to suppress the scanning cathode ray beam of a cathode ray image reproducing tube during the beam snap-back or return-trace, and for the purpose of maintaining all receiver units in synchronous operation with the transmitter when the video and control signals are received.

Output signal energy from the combining amplifier unit 29 is then supplied by conductor 31 to the control electrode 33 of the video amplifier or clipper tube 35 to control the signal energy flow therethrough. Output signal energy (representing the combined signal) is then derived from the amplifier 35 by way of its cathode 37 and the cathode load resistor 41 which connects at one of its terminals to ground at 39. The current flowing through the cathode output resistor produces the voltage drop which is transferred at the output terminal 43 to a suitable load circuit or utilization apparatus (not shown).

Operating voltages for the tube 35 are provided by way of an energy source (not shown) having its positive terminal connected at terminal 49 and arranged to supply operating voltage to the plate or anode 38 of the tube 35 by way of the peaking inductance element 47 and the plate load resistor 45. Suitable bias is applied to the control electrode 33 of the video amplifier 35 by way of the conventionally indicated bias resistor 40. The bias or clipping level on tube 35 is set automatically by the resistor 40, for instance.

An automatic volume control diode tube 59 is connected so that its plate or anode 57 connects by way of the coupling condenser 53 and conductor 51 to the junction point 50 of the plate output resistor 45 and the peaking inductance 47. The resistor 45 can be used in the connection shown to improve the frequency characteristic of tube 35. The anode 57 of the diode 59 is likewise biased to ground by way of resistor 55. In the arrangement disclosed, it will be apparent that with the signals for operating the tube 59 being derived from the inductance or choke element 47, only the higher frequency video signals will become effective at the anode 57 of this diode 59.

To establish a control cycle for the operation of the diode element 59, in order that the diode may be restricted in its operative periods to those when useful video signals are to be derived from the output terminals 45, the cathode 61 of the diode element 59 connects to ground 39 by way of the cathode resistor 67 and blanking signals of positive polarity are supplied at the terminal input 63 and fed by way of the coupling condenser 65 to the diode cathode 61 across the resistor 67. In this way, the cathode element 61 of the diode 59 is carried highly positive relative to its anode or plate 57 each time a blanking signal is impressed at the input terminal 63. Under these conditions, the diode element 59 ceases to draw current and it becomes inoperative as an automatic volume control tube during the periods when blanking signals are supplied. Otherwise, a control voltage is developed to become effective in the conductor 69 which connects the diode 59

to the amplifier 27 so that the amplifier is controlled under the influence of the current flow condition in the diode element 59.

In the lead or conductor 69 connecting the diode 59 back to the amplifier 27, there is included a filter combination comprising the resistor 71 and the capacitor 73 shunting it to ground 39. This filter is so designed and operated that any video or picture signal current which might flow in the conductor 69 is filtered out, and the voltage which reaches the amplifier 27 to control it is a measure of the effect of the diode 59 to establish a predetermined signal level output from the amplifier 27. Resistor 73 is a protective resistor for usual purposes. While not illustrated, it will be appreciated that the diode voltage which is effective on the tubes of amplifier 27 is applied in such a known manner as to bias one or more of the control electrodes to such a value that the output signal level is established by the diode current.

In the operation of the system described, it will be appreciated also that if the diode tube 59 is rendered ineffective to produce a control voltage for the amplifier 27 during the blanking period or interval, and with the filter combination 71 and 73 serving to filter any video or picture signals from being fed back, the control voltage effective upon the amplifier 27 to set its gain level will be that voltage which is a measure of the signal level variation during the video signalling period and will not be disturbed by conditions which occur to cause undesired signals during blanking intervals.

While the form of invention hereinabove explained illustrates a circuit wherein the voltage for operating the automatic volume control has been derived from the plate or anode circuit of the clipper tube by the connection at point 59, a modification might readily be made where the controlling voltage was derived from a similar connection made to the input circuit of the clipper tube 35. This, for instance, might be by way of a connection established on the conductor 31 and substantially at the grid or control electrode 33 of the clipper tube 35.

It, of course, will be appreciated, under such circumstances, that the polarity of the signal supplied to the diode 59 must be made to correspond to that with the circuit diagram shown when the modification above suggested is made so that a relay or reversing tube may frequently be used. Alternatively, where the signal polarity is such as to demand it, the diode connections may be reversed and a negative synchronizing impulse applied at terminal 69.

Having now described the invention what is claimed is:

1. In a television video system wherein produced video signals are amplified and combined for transmission with at least one control signal occurring at predetermined spaced time intervals, a signal output control comprising an amplifier for combining and amplifying the produced signals, a rectifier element connected to receive signal energy output from the amplifier and normally to draw current which is a measure of the average signal output level, means for applying a bias voltage to the amplifier under the control of the current flowing through the rectifier, and means to render the rectifier inoperative to apply the said bias voltage during the periods where the control signals are combined with the video signal.

2. A television system comprising means to pro-

duce trains of video signals, a source of control signals occurring for predetermined time periods and with predetermined time spacings therebetween for combination with the produced video signals, a video signal amplifier unit, a combining amplifier unit for combining and amplifying the video and the control signals, an output amplifier, a rectifier element, means for supplying energizing voltages to the rectifier from the signal output of the output amplifier, means for applying a bias voltage to the video signal amplifier to control the signal amplification therefrom in accordance with the current flow through the rectifier, and means for keying the rectifier by the control signals to limit the operative periods of the rectifier to time intervals intermediate each control signal.

3. An automatic volume control system for television amplifier units comprising a video signal amplifier unit, a source of signals regularly occurring at spaced time intervals for controlling the video signals, a combining amplifier for combining the amplified video signals and the control signals, means to supply the combined signals to a load circuit, a rectifier element, means to energize the rectifier by the produced combined signals whereby the current flow through the rectifier represents the signal output level of the amplifier unit, means to supply a control voltage to the video signal amplifier which is determined by the current flowing through the rectifier, and means also to supply the control signals from the source to the rectifier to control the rectifier independently of the combined video and control signals in a manner to bias the rectifier to a cutoff state during periods when the control signals are present.

4. A television video amplifier system wherein produced video signals are amplified and combined for transmission with at least one control signal occurring at predetermined spaced time intervals following a series of video signals comprising an amplifier for combining and amplifying each of the produced video and control signals, a rectifier element connected to receive signal energy output from the amplifier and normally to draw current determined by the average signal output level from the amplifier, means for developing a bias voltage under the control of the current flowing through the rectifier and for applying said voltage to the amplifier, and means to render the rectifier inoperative to develop the said bias voltage during time periods where the control signals are combined with the video signal.

5. A television system comprising means to produce trains of video signals, a source of control signals occurring for predetermined time periods and with predetermined long time spacings therebetween as compared with the signal duration for combination with the produced video signals, a video signal amplifier unit, a combining amplifier unit for combining and amplifying the video and the control signals, a diode rectifier element, means for supplying energizing voltages to the said diode rectifier from the signal output of the combining amplifier, means for developing a bias voltage to be applied to the video signal amplifier to control the signal amplification therein with the bias voltage being developed in accordance with the current flow through the said diode rectifier, and means for keying the said diode rectifier by the control signals to limit the operative periods of the rectifier to time intervals intermediate each control signal.

6. An automatic volume control system for television amplifier units comprising a source of video signal energy, a source of control signals regularly occurring only at spaced time intervals relative to the video signals, a combining means for combining the said video signals and the control signals into a combined video and control signal wave train, means to supply the combined signals to a load circuit, a rectifier element, means to supply the combined signals to the rectifier to control the current flow therethrough in accordance with the signal level of the combined signals so as to develop a control voltage proportional to the current flow, means to supply the control voltage to control the signal level of the signals supplied to the load circuit, and means also to supply the regularly occurring control signals to the rectifier to control the rectifier independently of the combined video and control signals in a manner to bias the said rectifier to a cutoff state during periods when the control signals are present.

7. In a television video system wherein produced video signals are amplified and combined for transmission with at least one control signal occurring at predetermined spaced time intervals, a signal output control comprising an amplifier for combining and amplifying the produced signals, a rectifier element connected to receive signal energy output from the amplifier and nor-

8
mally to draw current which is a measure of the average signal output level, means for applying a bias voltage to the amplifier under the control of the current flowing through the rectifier, and means to supply the control signals to the rectifier independently of the combined signals to render the rectifier inoperative to apply the said bias voltage during the periods when the control signals are combined with the video signals.

10 8. A television system comprising means to produce trains of video signals, a source of control signals occurring for predetermined time periods and with predetermined long time spacings therebetween as compared with the signal duration for combination with the produced video signals, a video signal amplifier unit, a combining amplifier unit for combining and amplifying the video and the control signals, a diode element having its anode electrode element connected to receive combined video and control signal output energy, means for developing a bias voltage for the video signal amplifier to control the signal amplification therein in accordance with the current flow through the diode, and means for applying the control signals in positive polarity to the diode cathode for keying the diode thereby and limiting the operative periods thereof to time intervals intermediate each control signal.

WALDEMAR J. POCH.
